UNITED STATES PATENT OFFICE.

CHARLES WENY, OF CHICAGO, ILLINOIS, ASSIGNOR OF ONE-HALF TO
RUDOLPH MUELLER, OF CHICAGO, ILLINOIS.

VINEGAR APPARATUS.

No. 823,570.

Specification of Letters Patent.

Patented June 19, 1906.

Application filed October 28, 1905. Serial No. 284,875.

To all whom it may concern:

Be it known that I, CHARLES WENY, a subject of the Grand Duke of Luxemburg, residing at Chicago, in the county of Cook and State of Illinois, have invented new and useful Improvements in Vinegar Apparatus, of which the following is a specification.

This invention is an apparatus for automatically sprinkling or distributing the infusion in generators of vinegar factories, and has for its object to provide a single evacuation which will be common to all of the generators of a single group and so constructed that each generator of the group will get the same definite quantity of liquid at the same time.

The object of the invention is to provide an improved device which will not require manual assistance or operation and which is not too complicated to insure a regular and perfect working.

A further object of the invention is to provide such an apparatus with devices which will not clog and also in which the sprinkler and infusion are entirely shut off from the atmosphere, thereby preventing any loss of alcohol from evaporation. By the same means dirt and insects are kept out of the vinegar.

The invention is illustrated in the accompanying drawings, in which—

Figure 1 is a sectional elevation showing several floors of a factory provided with the invention. Fig. 2 is a section of the first receiving or pressure tank, with a float-valve therein. Fig. 3 is a detail in section of said valve. Figs. 4, 5, 6, and 7 are sectional views of the evacuation or siphon tank, and Fig. 8 is a plan view thereof. Fig. 9 is a sectional view of one of the distributers in the generator.

The vinegar mash or liquor is first contained in a supply-reservoir tank A, to which is connected a pipe b, having a cock a leading to a float-valve c and into tank B, from which it is delivered by a pipe e into the evacuation or siphon tank C, and said pipe e has a cock f. By means of a system of siphons, herein-after described, the liquor is fed into the supply-pipe h, from which it is delivered by siphons i into sprinklers l, which rotate in the generators D. After the mash has passed through the first set of generators it is trans-

ferred through outlets q into drain-pipe r and through pipe s into a similar evacuation or siphon tank C' on a lower floor, from which it is delivered to the second set of generators D', after passing through which it escapes by the pipes q' and r' and pipe s' as vinegar into the reservoir E in the basement or lower floor.

The details of the float-valve in the receiving-tank B are shown in Figs. 2 and 3, and this valve regulates the flow of the mash from the reservoir into said tank, so that a constant level is maintained in the tank, and consequently there is always the same pressure on the discharge of the mash to the siphon-tank. The body of the float-valve is indicated at c and has a cross-plug c', the projecting ends of which are threaded to receive lock-nuts by means of which the fork d' is fastened to the plug, said fork being a continuation of the arm d, the free end of which carries a float d². The plug c' has an inlet-hole c⁴, registering with the bore c³ in the body c, and liquid entering through said hole escapes from each end of the plug. As the float rises and lowers the valve is closed and opened, maintaining a substantially constant level.

The cock f on the pipe e, which connects the tanks B and C, may be adjusted to control the flow of liquor through said pipe, so that the tank C will be filled with a certain quantity during a certain time. As soon as the mash in the tank C reaches a sufficiently high point the siphons come in operation to discharge the mash in the tank to the generators.

The main siphons consist of a pair of pipes g' and g⁹, which are connected by flexible sections g⁵, so that the inner parts of the siphons may be lifted or lowered. Said inner parts g⁹ are mounted upon a cross-shaped wooden float or base g³, having legs g¹², which prevent the mouths of the siphons from coming against the floor of the tank, and so being obstructed. The lower ends of the siphon-sections g⁹ pass loosely through holes in one of the cross-pieces forming the wooden frame and are held in proper position or adjustment by means of nuts g¹⁰ and g¹¹, which are rounded on the bottom to allow the pipe to swing and the frame g⁸ and vessel g to remain level at all times. This jar or vessel g is mounted upon the floating frame g³ and has therein a

small siphon g^3 , which extends through the bottom of the jar and below the frame. At the top of the tank is a stop g^4 , adjustable by means of screws g^6 .

5 As the mash flows into the tank C the floating frame rises until the elbows of the sections g^9 reach the stop g^4 . Then the jar g , which is fastened to the floating frame, begins to fill through the small siphon g^2 . As 10 soon as the jar is filled it sinks by its own weight to the bottom of the tank, carrying with it the frame and the sections g^9 of the main siphons, which then begin to discharge into the pipe h and continue to discharge 15 until all the liquor in the tank is drawn off, after which the operation is repeated as the tank is again filled through the pipe e .

As the main siphon-pipes g^9 extend somewhat lower into the tank than the siphon g^2 , 20 the jar g is emptied through the latter before the former stop drawing. The pipe h carries the mash to siphons i , of which there is one for each generator. Each siphon i is of the 25 same capacity, so that the same amount of liquor is distributed to each generator; but by raising or lowering the short legs of the siphons in the pipe h (see Fig. 9) the quantity 30 may be varied to a limited extent. The siphons i discharge into funnels k , which are closed so that no insects or dirt can enter. 35 From the funnels the liquor passes through the tops of the generators into rotary sprinklers consisting of a series of radial arms l , which have holes in the sides, causing the 40 arms to rotate in consequence of the flow of the liquid through the holes.

The evacuation-tank C is preferably provided with a gage-glass g^8 and scale g^7 , so that it can be seen how much time is taken to fill 45 the tank, and accordingly the time can be regulated by means of the cock f , and when once set will stay the same, because of the constant head in the tank B. This is an important feature and insures a flow of mash to the generators which is regular as to both 50 quantity and time.

It will be seen that at no place is the liquor exposed to the air, since all the connections or joints are closed. The fittings are preferably made of hard rubber, because it does not break as easily as glass nor burst like wood, and can easily be cleaned. The material, however, is a matter of choice. Although 55 illustrated in connection with a vinegar apparatus the invention may be applicable to other uses, and the scope of the invention is not limited to the exact embodiment shown.

Having thus described my invention, what is claimed as new, and desired to be secured by Letters Patent, is—

60

1. In a vinegar apparatus, in combination, a supply-tank having means to maintain a constant head therein, an evacuation or feeding tank connected to the generators, and a connection between the supply-tank and the 65 evacuation-tank having means to deliver a predetermined quantity of liquid to the latter in a certain time.

2. An evacuation-tank for a vinegar apparatus having a floating jar and main siphon 70 therein, the jar having a siphon extending through the bottom of the same and arranged to fill the jar and sink the main siphon when the liquid in the tank reaches a certain height.

75

3. An evacuation-tank for a vinegar apparatus having a float therein and a jar mounted on the float, a siphon having two legs connected by a flexible section, the inner leg being mounted on the float and the outer leg 80 extending through the wall of the tank, and a siphon carried by the jar and arranged to fill the same and sink the float at a certain height.

85

4. An evacuation-tank for a vinegar apparatus, having therein a float carrying a jar and a main siphon, an adjustable stop at the top of the tank arranged to limit the rise of the float, and a small siphon carried by the jar and arranged to fill the same and sink the 90 float after the rise of the float is arrested by the stop.

95

5. An evacuation-tank for a vinegar apparatus, having therein a float having depending legs, a pair of flexible siphons the inner legs of which are attached to and open under the float, a jar mounted on the float between the siphons and having extending through the bottom thereof a small siphon, and a stop for the float in the top of the tank.

100

6. In a vinegar apparatus, the combination with a generator having a sprinkler therein, and a supply-pipe, of a funnel connected to the sprinkler and having a closed top, and a siphon which taps the pipe and extends into the funnel.

105

In testimony whereof I have signed my name to this specification in the presence of two subscribing witnesses.

CHARLES WENY.
